DESIGN FOR A HOLLOW DOUBLE-WALL GLASS REFLECTOR

Carl E. Anderson and Carl R. Palmer, Steubenville, Ohio

Application August 28, 1935, Serial No. 58,347

Term of patent 14 years

To all whom it may concern:

Be it known that we, Carl E. Anderson and Carl R. Palmer, both citizens of the United States and residents of Steubenville, in the county of Jefferson and the State of Ohio, have invented a new, original and ornamental Design for Hollow Double-Wall Glass Reflector, of which the following is a specification, reference being had to the drawing accompanying, and forming a part thereof:

In the drawing, Fig. 1 is a side elevational view of a hollow double-wall glass reflector showing our new design, and Figs. 2 and 3 are a bottom

plan view and a cross sectional view, respectively, of the reflector illustrated in Fig. 1.

The design is characterized by a plurality of intersecting arcuate grooves in the inner surface of the reflecting wall, the outer surface of the reflecting wall being smooth.

We claim:

The ornamental design for a hollow double-wall glass reflector, substantially as shown and described.

CARL E. ANDERSON.
CARL R. PALMER.
